Attorney.

UNITED STATES PATENT OFFICE.

WILLIAM C. BAESSEL, OF PROVIDENCE, RHODE ISLAND.

CLOTHES-LINE FASTENER.

1,049,642.

Specification of Letters Patent.

Patented Jan. 7, 1913.

Application filed October 24, 1911. Serial No. 656,414.

To all whom it may concern:

Be it known that I, WILLIAM C. BAESSEL, a citizen of the United States, residing at the city of Providence, in the county of Providence and State of Rhode Island, have invented certain new and useful Improvements in Clothes-Line Fasteners, of which the following is a specification.

My invention relates to a device essentially designed for use as a fastener for lines on which clothes are suspended; and has for its objects to provide two members having each a large flat bearing surface, to act as holding points upon the sides of the line and extending parallel therewith; means to force one of said members into firm contact upon the line, and means for adjusting the device to suit the size or thickness of line to be clamped in position.

In the accompanying sheet of drawings, Figure 1 is a plan view of my improved device, showing a clothes line secured thereon. Fig. 2 is a side sectional view taken on line $x-x$ of Fig. 1, showing the parts embodying my improvements, and, Fig. 3 is a detail portion of the device.

Like reference characters indicate like parts.

In carrying out my invention I provide two disk clamping members a and b , designed to hold the clothes line 1 therebetween.

The member a has an integral angle piece a^1 which is perforated to receive screws s , s for securing the device to a wall or post p , and centrally of the disk portion of said member a is a downwardly extending head a^2 having a circular aperture a^3 projecting from a flat bearing surface a^4 of said member.

The member b has a central annular flange b^1 extending downwardly from a flat bearing surface b^2 of said member, and said flange has a sliding fit within the aperture a^3 of the member a .

A bolt c has one end pivotally connected by a pin d to an integral cam part e of a hand lever e^1 , this portion of said bolt having flat faces, as c^1 , c^2 , to fit the sides of a rectangular slotted opening a^5 formed through the closed end a^6 of the head a^2 , and the other end of said bolt provided with a screw-threaded portion c^2 which passes through an opening b^3 formed through the closed end b^4 of the clamping member b .

A nut f on the threaded portion of the bolt c is made to bear against the top of the clamping member b .

An expanding coil spring g surrounds the bolt c and is interposed between the respective closed ends a^6 and b^4 of the clamping members a and b .

The connecting portion of the hand lever e^1 is bifurcated to receive the flattened part e^2 of the bolt c , in the manner shown in Fig. 3, and the surrounding part of this portion of said lever disposes a cam face, as e , for contact upon the flat bearing face a^7 of the head a^2 .

To secure the clothes line 1 to the device, the lever e is brought to its dotted position shown in Fig. 2, when the lowest rise of cam e is then had upon the head a^2 and allows the action of spring g to carry upward the clamping member a , to its dotted position of parts shown in said figure.

The space between the members a and b is now sufficient to pass the line 1 between their bearing surfaces a^4 and b^2 , after which the lever is swung to its full line position shown and thereby cause the member b to force down and firmly secure the line in place upon the device.

The highest point of the cam e causes the device to be brought to a clamped position and in order to hold the lever from displacement while in this position this point of its cam is made flat, as more clearly shown at e^2 in the dotted position of said lever.

The members a and b are designed to extend parallel with the clothes line 1 and by having these members provided with large flat surfaces, as a^4 and b^2 , for contacting upon said line, serves to prevent the latter from becoming ragged or fragile at its points of securing.

By means of the nut f the latter may be turned one way or the other in adjusting the clamping member b , to obtain the proper space desired between the members a and b , for entering of the clothes line upon the device.

Having thus described my invention, what I claim and desire to secure by Letters Patent is:

In combination, a disk-shaped fixed jaw having a central bored hub, said jaw provided with a rectangular opening in its hub; a disk-shaped movable jaw having an annular flange slidable in the bore of the hub,

said movable jaw provided with a circular opening; a bolt having a screw-thread at one end and passing loosely through the opening of said movable jaw and the other end of said bolt having opposed flat sides to prevent turning in the opening of said fixed jaw and said bolt provided with a perforation through its flattened part; a thumb-nut engaging the thread of said bolt to permit adjusting said movable jaw; a pin through the perforation of said bolt; an expanding coil spring surrounding the latter,

a lever having a bifurcated head pivotally connected to said pin, the head having cam faces to bear against the hub to permit said lever to carry inwardly the movable jaw to a normal fixed position, as shown and for the purpose specified. 15

In testimony whereof I affix my signature in presence of two witnesses.

WILLIAM C. BAESEL.
